UNITED STATES PATENT OFFICE.

JAMES H. MCLEAN, OF DAYTON, OHIO.

DESIGN FOR A LOAF OF PREPARED MUSH.

SPECIFICATION forming part of Design No. 28,242, dated February 1, 1898.

Application filed September 20, 1897. Serial No. 652,380. Term of patent 14 years.

To all whom it may concern:

Be it known that I, JAMES H. MCLEAN, a citizen of the United States, residing at Dayton, in the county of Montgomery and State of Ohio, have invented and produced a new and original Design for a Loaf of Prepared Mush, of which the following is a specification, reference being had to the accompanying drawings, forming a part hereof.

10 Figure 1 is a perspective view of a loaf of prepared mush showing my design. Fig. 2 is an end view of the same, and Fig. 3 is a side view thereof. These three views are deemed necessary to fully illustrate my design.

15 The leading feature of my design for a loaf of prepared mush consists of a cylinder the length of which is about three times its

diameter and having its ends in the form of a rosette the faces of which taper toward the center, but project outwardly. ²⁰

A and B are the ends and C the side of the cylinder of prepared mush. Said ends are bulging outwardly, and on each one is formed a rosette. The faces *d* of each taper outwardly toward the center and terminate ²⁵ in a small circle *e* in the center of the bulge.

What I claim is—

The design for a loaf of prepared mush as herein shown and described.

JAMES H. MCLEAN.
